Inc., Chicago, Ill., a corporation of Illinois

Application December 17, 1956, Serial No. 44,213

Term of patent 14 years

(Cl. D15—8)

The dominant features of my design reside in the portions shown in full lines.

I claim:

The ornamental design for a stool, substantially as shown and described.
